UNITED STATES PATENT OFFICE

CHARLES W. WALLER, OF CHICAGO, ILLINOIS

FLYING MACHINE

Application filed July 7, 1928. Serial No. 290,929.

My invention relates to improvements in flying machines of the type adapted to rise and descend vertically and more particularly to such machines of the type adapted to be raised, sustained and propelled through the air by one and the same element or elements and has for its primary object to provide and improve the construction, arrangement and relative disposition of the respective lifting, 5 sustaining and propelling element or elements and load, by which said element or elements are disposed at the upper-most portion or end of said machine, the weight of its frame or body, including the power plant, 10 operator, passengers and freight, if any, being disposed at the lower-most portion or end of the machine, the said lifting, sustaining and propelling element or elements being further disposed above said frame or body, etc., 15 and both said element or elements and frame or body, etc. being further disposed in the vertical line of the center of gravity or vertical axis of the machine while in flight, thus acting as a gravity balancing means, possessing 20 inherently, and thereby maintaining, both longitudinal and lateral stability, tending constantly to keep the machine in a state of poise regardless of winds, etc., and thus making it easy to handle in the air by any one who 25 is not a skilled pilot and who is, at all times free from the act of balancing the machine and which machine thus not being susceptible to the prevention of flying on account of certain weather conditions, and also avoiding 30 the casualties attributable to the machine losing its balance, etc., as well as to simplify the controlling of the longitudinal direction of flight.

Another object is to provide a machine of 35 this character which will more efficiently utilize and take advantage of natural laws governing and controlling the lifting, sustaining and propelling capacities of aerial craft, and in which the lifting element or elements are given as far as possible a form constructed 45 and adapted to present a more effective sustaining surface on their underside as well as being adapted to more effectively lessen and maintain the least possible air resistance or 50 pressure on their upper side and to give max-

imum support on their under side in proportion to their weight and size, whereby a greater load sustaining area, and a higher degree of flying is secured.

Another object of the invention is to provide a machine which will be safe in case of accident in the air and the lifting, sustaining and propelling element or elements so constructed that it will act as a parachute by interposing sufficient air resistance to secure a rapid parachutic action and reduce the falling speed while maintaining the machine upright, and further, to provide a machine capable of having one or more large common parachutes stored away therein, normally out of the way, and in case of accident in the air, adapted to be instantly ejected into the free air to support the entire machine, thereby making it unnecessary for the operator and passengers, if any, to make a dangerous parachute jump and thereby insuring a safe and easy descent.

A further object of the invention is to provide a machine having a new form of combined shock absorbers and landing devices.

A further object of the invention is to provide a machine having as far as possible a form of lifting element or elements constructed to form a hollow chamber filled with air or some gas lighter than air to give maximum air displacement and support in proportion to its weight, thereby obtaining both strength and lightness combined.

A still further object of the invention is to provide a flying machine which will not take up much ground area, relative to its weight-lifting capacity.

A still further object is to provide a flying machine capable of rising and descending either vertically or diagonally, thus being adapted to rise from and land on a small area of ground or the flat roof of a small building, if desired or necessary, and eliminating the necessity of going to and from flying fields or air ports in order to take to the air and land when making an aerial flight.

With the foregoing and other objects in view, which I attain and which will appear as the description proceeds, the invention con-

sists in the novel construction, arrangement and combination of parts, hereinafter described, illustrated in some of its embodiments in the accompanying drawings, and particularly pointed out in the appended claims, it being understood that changes in the precise embodiments of the invention herein disclosed can be made within the scope of what is claimed without departing from the spirit of the invention.

In the accompanying drawings, forming a part of this specification, the preferred form of the invention has been shown, in which:—

Figure 1 is a vertical section of the entire machine, on line 1—1 of Fig. 8, and looking in the direction of the arrow;

Figs. 2 to 4, vertical sections of modified forms of reciprocating propellers;

Fig. 5, a top plan view of the steering mechanism;

Fig. 6, a side vertical sectional view thru its longitudinal center line, of an electrically powered modified form of the invention employing only one reciprocating propeller, the lateral brace bars on one side not shown;

Fig. 7, a similar view of a similar electrically powered modified form of the invention employing a plurality of lifting and propelling devices, the lateral brace bars on one side not shown;

Fig. 8, a front elevation of Fig. 1;

Fig. 9, a side elevation, partly in section thru its longitudinal center line, of a modified form of reciprocating propeller which resembles an airplane wing section and operating mechanism therefor, the lateral brace bars on one side not shown;

Fig. 10, a side elevation, partly in section near its longitudinal center line, of a modified form of the invention employing a plurality of reciprocating propellers, and means for shifting a load or weight backward or forward in order to change its center of gravity or forward tilt of the machine as a whole for upward and forward flying, the lateral brace bars on one side not shown;

Fig. 11, a side vertical section of a modified form of motive power employing independent plural motors adapted to independently operate at will, the reciprocating propellers shown in Fig. 10, either one alone, or both independently and simultaneously;

Fig. 12, a side elevation of means for reducing the relative speed of the reciprocating propeller or propellers;

Fig. 13, a vertical section of the entire machine, on line 13—13 of Fig. 14, looking in the direction of the arrow, of another modification of the form of the invention shown in Fig. 1, and in this instance employing another modified form of reciprocating propeller, and showing a protective guard for said device;

Fig. 14, a top plan view of Fig. 13, with

the protective guard and some of the parts of the steering mechanism removed;

Fig. 15, a side vertical section, substantially at its longitudinal center line, of still another modification of the form of the invention shown in Fig. 1 and which, in this instance, employs two other modified forms of reciprocating propellers, the lateral brace bars on one side not shown;

Fig. 16, a top plan view of a still further modified form of the invention in which a plurality or series of the reciprocating propellers are employed; and

Fig. 17, a vertical section of a modified form of one of the reciprocating propellers, shown in Fig. 15.

Similar numerals refer to similar parts throughout the several views of the drawings.

Referring to the drawings, the improved machine comprises a suitable frame or frame structure 1, made up and suitably braced in the present instance, of a plurality of longitudinally extending bars 2, suitably connected by means of a plurality of connecting transverse rings or circular members 3.

The frame may also, if desired, be provided with any suitable covering 4, such as, for instance, aluminum or fabric, to form a streamline body or shell 5, which serves as a car or carrier for the operator, power plant, steering mechanism, and passengers, if any, or other load, and also as a main pontoon for supporting the machine in a body of water, and said frame or body being slightly inwardly turned to a suitable point or angle at its forward end, thus effecting a minimum degree of head resistance.

Secured to and carried by this frame is the lower portion or end of an upright member 6 of any suitable form thru its horizontal cross section, such as, for instance, L, H, T or U shaped, but in the present instance, it is circular or O shaped in form, which member may be either vertical or forwardly tilted or inclined, and in the present instance, being slightly forwardly leaning and disposed in the medial fore and aft line of the frame at any suitable transverse point, preferably near its transverse center.

If said member is vertically disposed instead of forwardly inclined, a reciprocating propeller 7 is so superposed or disposed at the upper portion or end of said member 6 as to permanently retain its present forward tilt or angle, thus permitting the weight of the operator, motor and other load to be disposed forwardly of and closer to said member 6 and thus also disposing the vertical axis of said machine closer to, as well as forwardly of, said member.

In order to provide a wide landing and resting base or foundation for the machine to retain its upright position when making a landing and when at rest on the ground, there

- is also secured to the frame or body at the front center thereof and preferably extending forwardly, laterally, and slightly downwardly from said frame front center, front 5 lower braces 8, and similar rear lower braces 9 extend similarly from the rear center of said frame, and suitable upwardly and inwardly inclined brace bars 10 extend from each free or lateral end of the braces 8 and 10 9 to the upper or intermediate portion of the upright member 6, the upper end of each of said brace bars being suitably secured to a horizontal and preferably transverse bolt or pin 10^a, such as, for instance, by means of 15 suitable lock nuts 12, and if desired, said upright member, braces and brace bars, may be given, as far as possible, a stream-line form fore and aft, effecting a minimum degree of head resistance.
- 20 At the upper portion or end of the upright member 6 is superposed and slidably mounted a reciprocating propeller 7, which device may be formed of any suitable material, such, as, for instance, solid or sheet metal or solid, 25 sheet or plastic wood, presenting a concaved underside, or so formed as to utilize its entire underside or lifting surface for lifting and sustaining the machine in the air, thereby getting the most possible amount of lifting 30 and sustaining efficiency therefrom, such as, for instance, having any suitable concavo-convex shape or form, but preferably being substantially funnel shaped or having its wall disposed at substantially a 45 degree angle, the upper or convex side extending forwardly or longitudinally in the direction of flight, as illustrated by Figs. 1, 6, 7, 8, 10, 13, 35 14 and 15 of the drawings.
- However, I do not wish to limit myself to 40 any specific form of concavo-convex reciprocating propeller, and may, if desired, employ one or more of such propellers of the same or different forms or construction interchangeably, such as, for instance, any one or 45 more of those shown in Figs. 1 to 4, inclusive, Figs. 6 and 7, 9 and 10, 13, 15 and 17, or otherwise, so long as the form or shape of their main wall or side is concavo-convex.
- If desired, both the convex and concave 50 surfaces 14 and 145 and 14^a and 146, respectively, of the device 7 (see Figs. 1 and 10) may be formed or disposed at an angle greater or lesser than 45 degrees, such as, for instance, the convex surface disposed at approximately 55 20 or 60 degrees, or the convex surface formed at a greater angle than 45 degrees, while the concave surface may be formed to be disposed at a lesser angle than 45 degrees, such as, for instance, approximately 10 or 20 degrees, and provided with a hollow interior 13 for containing either air or a gas lighter than air.
- The concavo-convex form of the propeller or propellers 7 would also function as one or 60 more parachutes, as the case may be, in case of any trouble in the air and a fall of the machine to the ground takes place.
- In the present instance in order to more efficiently create a high partial vacuum above, the propeller 7, the lower edge or portion of 70 the outer surface of the wall 14 is disposed inwardly, the said wall being thinnest at its lowest point 15 and thickest at its highest point 16, thus giving it great strength to withstand the rapid or high speed reciprocal motion in the operation of the machine, but may, if desired, be thinnest at its highest point and thickest at its lowest point, the upper end of said propeller being connected to a substantially vertical slidable member 75 16^a, which may be of any suitable form and mounted slidably to the upright member 6 in any suitable manner, but in the present instance it is fitted over or embraces said member 6, and in order to prevent said slidable 80 member from turning on its substantially vertical axis, substantially vertical lateral slots or openings 18 are provided thru the sides of said member 16^a thru which slots the bolt 10^a passes and past which bolt the 85 member 16^a rapidly reciprocates substantially vertically in operation.
- The lower end of said member 16^a is provided with a short horizontal projection 19 which connects preferably movably with the 90 upper end or bearing 20 of a substantially vertical driving rod 21, and secured by suitable lock nuts 22, a similar lower end or bearing 23 of said rod 21 movably connecting with a crank or eccentric 24 which is driven 95 or actuated in the present instance by any suitable form of conventional type of power, such as, for instance, a motor or engine 25, but may be also, if desired, adapted to be operated by manual power, such as by the 100 arms or legs of a person, and inasmuch as the specific power plant in itself forms no part of the present invention, it is not shown in detail and I may, if desired, even employ electric motive power of any suitable conventional form, such as, for instance, an electric solenoid 26, as shown in Fig. 6 and which will hereinafter be more fully described, the upper portion of said frame 1 being provided with an opening 21^a thru which the 105 driving rod 21 reciprocates substantially vertically.
- If desired to operate or reciprocate the propeller or propellers 7 at the same speed as the motor, said propeller or propellers may 110 be connected direct to said crank or eccentric, or the speed of said crank and said propeller or propellers may be decreased relative to the speed of the motor and also to reduce the strain on said motor and the pull of said 115 motor relatively increased by means of a pinion 28 on the shaft of the motor 25 which pinion meshes with a gear or gear wheel 29, said gear being connected to said crank, or 120 said propeller or propellers 7 may, if desired, 125
- 65 more parachutes, as the case may be, in case 130

be operated rapidly by short strokes by any suitable manner of connecting said motor to said crank, the free end of shaft of said crank supported in a bearing 153 secured to the top 5 of said motor, shown in Fig. 12.

The propeller or propellers 7 are preferably disposed at the highest possible point of the machine, that is, at the uppermost portion or end of the upright member 6, said 10 member extending upwardly from the frame or body and tilted forward at any desired degree, such as, for instance, at approximately 70 or 80 degrees, said forward tilting of said member 6 and propeller or propellers 7 being permanently fixed, as shown in Figs. 1, 15 8, 13, 14 and 15, but being caused by the weight of the useful load (comprising the operator, motor, and passengers, if any, etc.) being carried at substantially the lowest portion 20 of said machine and directly beneath the center of lift of said propeller or propellers 7, which center of lift of said propeller or propellers and the center of weight or gravity of said frame 1 constituting or 25 comprising the substantial vertical axis of said machine, as shown by the broken line 99 of Figs. 6, 7 and 10.

In the present instance, the free end portion or crank shaft 30 of the crank 24 passes 30 thru the lower portion of the member 6, which lower portion functions as a bearing or mounting for said free end portion of said crank, and while I have shown only one crank and driving rod 21, the end portion 35 or crank shaft 30 may be extended to connect with a second crank and driving rod, disposed on the opposite side of said member 6, not shown, but similar to said first mentioned crank and driving rod.

40 As a means of protecting the machine when it descends to the ground, suitable landing and resting devices 31 are provided, which devices may be either in the form of wheels similar to the wheels 107^a and 107^b 45 in Fig. 10, or 140^a, 142^a, and 144^a in Fig. 13, or as in the present instance, in the form of suitable cushion or shock-absorber members and being preferably air inflated flexible balls disposed beneath the connecting points 50 of the lower braces 8 and 9, and the brace bars 10 and beneath the approximate longitudinal and transverse center of the machine or beneath the lower end of the upright member 6, horizontal plates 32 of light material 55 being disposed between said braces and brace bars, and landing and resting devices, said cushion or shock-absorber members while resting on the ground, assuming a flattened out or horizontally disposed form or position, the form shown by the dotted line circle 33 in Fig. 8 being its normal shape while the machine is in the air or off the ground, while the horizontally disposed form shown in Figs. 1 and 8 being the shape assumed when 65 compressed between said plates 32 and the

ground by the weight of the machine resting upon them, the said plates assisting to flatten them out and making non-revolving frictional contact with the ground.

In order to reduce friction to a minimum 70 between the slidable member 16^a and the upright member 6, when said slidable member is given a rapidly reciprocating motion, suitable ball or roller bearings 34 are spaced at suitable distances and move in races or race- 75 ways designated by the dotted lines 35.

Since the propeller or propellers 7 are sealed as against the vertical passage of any air thru the same from the underside or concave surface to the upper or convex surface, and vice-versa, in the practical operation of the present invention, the machine is lifted and propelled forwardly by successive and rapidly repeated impulses, by said propeller or propellers being rapidly reciprocated substantially vertically by the operation of the crank or eccentric 24 by any conventional form of power, such as, for instance, by the hands or feet of a person, or, in the present instance, by the motor or engine 25 actuating 80 said crank, vertical driving rod 21 and slid- 85 able member 16^a, it is believed that a vacuum is formed or produced, such as, for instance, a partial vacuum, in the space approximately between the upper or convex surface of 90 said propeller or propellers 7 and the broken and dotted lines 36 just above said upper or convex surface, and owing to the said concave form or shape of the underside of said propeller or propellers, the air is caused to 95 be concentrated or compressed within said concaved space or underside of said propeller simultaneously with the forming of said vacuum and repeated at each and every downward stroke of said propeller or propellers, 100 the said propeller or propellers 7 being thus concentrated air or pressure on the under or concave surface and the formation of the vacuum above the convex side of said propeller or propellers, thus overcoming the force of 105 gravity and dragging or pulling the lower portion or frame of the machine below it thru the air and utilizing the said upward and downward forces to always maintain the machine in its upright position in the 110 air.

115 Thus it will be seen that at the same time that the vacuum forms above the upper or convex surface of the propeller or propellers 7 to remove the air pressure from above the same, which air pressure would otherwise bear downwardly against said upper or convex surface to retard its rising, the compression of the air taking place within the concave or under side of said propeller, and being prevented from escaping therefrom by 120 125 130

the concave underside of said propeller or propellers, the said air pressure bearing upwardly against the underside or surface of said propeller to raise it, similar to the principle of the wing of a common airplane being sustained in the air, except that said propeller or propellers 7 are reciprocated vertically thru the air, and the propeller or propellers 7 of the present invention being tilted forwardly more or less also serving to function as the forward propelling force instead of a common airplane propeller, as will be most clearly seen, Fig. 13 showing the propeller 7 as having moved upward in its reciprocating motion and ready to again move downward to create the said vacuum space, it being believed that the propeller 7, in proportion to surface area, has a greater lifting power than the common airplane wing, for the reason that the form or shape of the underside of the propeller 7 compresses and retains the air in a compressed state to a much greater degree, because this compressed air is held in a compressed state in its downward movement, instead of being permitted to flow on and escape, as is the case when a common airplane wing moves forwardly and horizontally thru the air.

As previously stated, while it is intended that the wall of the propeller 7 be permanently closed against the passage of air therethru vertically, in order to cause a vacuum to form above it and a compression of air to form below it, the propeller 7 may, if desired, be provided with a relatively small opening 37, disposed preferably thru the upper rear portion of the wall of said propeller, which opening would function to permit the escape of a relatively small amount of air and thereby assist in drawing air into the concave or underside of said propeller from below, similar to the effect of a small opening in the top of common parachutes, but I wish to have it understood, that this opening, may also, if desired, be entirely eliminated, it being understood that, if desired, the said propeller 7, being so adapted, may be employed on any other suitable type of flying machine giving a vertical rotary motion on a horizontal shaft, instead of a vertical reciprocating motion.

The different degrees of speed of the motor is controlled and regulated to determine the varied speeds of flight forwardly, upwardly, and, or, descend, in the present instance of this invention, by any conventional controlling or regulating means, not shown, and as a means for controlling the horizontal direction of flight, a vertical rudder 38 is disposed at one end of the machine, preferably at the rear, by means of the lower end of a vertical pole or stem member 39 being revolvably mounted to the frame 1 and the upper end of said pole member being similarly mounted to the free or rear end of a longi-

tudinally extending rod or bar 40, the forward or other end of said rod being suitably secured to the upright member 6, the free ends of a horizontal transverse rod or bar 41 connected to controlling cables or wires 42 and 43 and connected to a transverse steering foot lever 44 mounted in close proximity to the operator's seat 45.

In the present instance, as a means to economize in space, a part of the lower portion of the interior of the upright member 6 may be utilized as a liquid fuel storage tank or compartment 46, the fuel 47 having an outlet by means of a suitable outlet or supply pipe 48 connected to the motor or engine 25, the lower part of the said lower portion of the member 6 being utilized as a similar liquid oil storage tank or compartment 49 for the lubricating oil 50, which at all times keeps the free end portion or shaft 30 of the crank 24 properly lubricated, said fuel and oil tanks being provided with inlets 51 and 52 respectively, for replenishing the supply.

In order to further prevent any possibility of the propeller 7 slipping off the member 6 entirely in case the same should for any reason break away from the driving rod 21 or the latter should break away from the crank or the latter break away from its motor and bearing, the extreme upper end of the member 6 is provided with any form of suitable projection, such as, for instance, being flared outwardly or outwardly and downwardly to form a projection or flange, against which, in case of such an accident, the top end or apex 54 would abut and cause said propeller 7 to act or function as a parachute in the descent or fall of the machine to the ground.

As a further safeguard in case of an accident in the air, the upper portion of the interior of the member 6 may be utilized as a convenient storage space to inclose or house one or more large common parachutes 55 disposed above the conventional cables or ropes 56 which are preferably coiled and firmly secured to an upper eyelet 57 on the movable plug or plunger 58, a second or lower cable or rope 59 being coiled below and firmly secured to a similar lower eyelet 60, the free end 61 of said lower cable or rope passing around and firmly secured to the bolt or pin 10^a, the interior portion below said bolt being hermetically closed by an upper partition or plate 62 and a similar lower partition 63, forming a compressed-air compartment or tank 64, or if desired, may be in the form of a separate tank, an outlet valve or cock 56^a being disposed preferably above said upper plate or partition 62 or tank 64 and adapted to communicate with the interior of said compartment or tank.

If desired, the compressed-air tank may be of such large size that it will fill up the entire lower or almost the entire lower por-

tion of the interior of the member 6, or said tank may be located within the body 1 instead of within the member 6, and a pipe, not shown, may lead the compressed air to the space 72 above the partition 62 within said member 6.

Or if desired, the entire interior of the member 6 may be utilized for storing or containing a very large parachute or one or more 10 smaller parachutes and the means for ejecting them from the interior of said member 6.

In case of accident in the air, the said valve 56^a being adapted to be operated or opened at the will of the operator by any 15 suitable means, such as, for instance, by said operator pulling on the free end or ring 66 of the cable or rope 67 in close proximity to the operator's seat 45, said cable or rope passing over a lower guide pulley or member 20 68 on the frame 1 and an upper guide pulley or member 69 on one of the brace bars 10, the free end thereof being secured to the end of a lever 70, the other end of said lever being secured to a transverse lever arm or 25 bar 71 passing thru the substantially vertical slot 18 and secured to and connecting with the outlet valve or cock 56^a, which opens said valve to permit the compressed air (stored in the compartment 64) to rush out 30 and fill the space 72 and thus instantly forcing said plug or plunger 58 upwardly and out of the mouth of the member 6 and pushing or forcing the parachute or parachutes 55 and cables or ropes 56 out into the free 35 air, the rush of the compressed air upwardly from the mouth or interior of said member 6 assisting to fill the undersides of the parachutes 55 to assist in quickly opening them out for action against the lower air while 40 falling to the ground, the machine being suspended to the cable or rope 59 by means of the bolt or pin 10^a, and in addition to the parachutes 55 the parachutic form or shape 45 of the device or devices 7 also acting to assist said parachutes in breaking the fall to the ground, the said propeller 7 in the present instance, if desired, being, thru its center section, shaped similar to an airplane wing, as shown by the dotted line 73, or similar to 50 the propeller 7 shown in Fig. 9.

The numerals 74 and 75 indicate windows and a door, respectively.

Referring to the modified form of the invention shown in Fig. 6, the propeller 7 is 55 secured to an upright member 76 which is supported in its upright position by means of the upper ends of the brace bars 10 being, in this case, each secured to a collar 77 thru which said member 76 vertically reciprocates, the portion of said member 76 below 60 said collar 77 having movably fastened thereto, one above the other, substantially horizontal arms 78 and 79 and movably secured at 80 and 81, respectively, the movable 65 central portion of each arm provided with

a horizontal elongated opening 82 and 83, respectively, which permits easy movement of the said member 76 and arms 78 and 79, when they are vertically reciprocated by an electric solenoid 26, when an electric current 70 of any source is passed thru said solenoid, such as, for instance, from one or more electric batteries or storage cells 84, and its polarity rapidly and alternately changed automatically by the pole changer formed by one 75 end of the arm 78 being connected to the positive electric wire 85 and one end of the arm 79 being connected to the negative electric wire 86, and when the other, or either positive and negative ends of said arms are alternately rapidly reciprocated vertically 80 over the electric contacts 87, 88 and 89, when the electric switch 90 is closed, thus causing the positive electric current to flow, first into the wire 91 and thru the solenoid in one direction and then caused to flow into the wire 92 and thru the said solenoid in the opposite direction, to cause the upright member 76 to vertically reciprocate rapidly, the portion 93 of the member 76 being of magnetic material, such as, for instance, iron, and the remaining portion above and below said portion 93 being of any suitable light-weight non-magnetic material, such as, for instance, an aluminum rod or brass tubing, it being 90 understood that I may, if desired, substitute an electric rheostat instead of the electric switch 90, as shown by 94 in Fig. 7, the extreme lower end of said member 76 being provided with a horizontal projection 95, to 100 prevent the said member 76 from sliding out of the machine entirely, the propeller 7 in the present instance, being, if desired, entirely closed near its lower portion or mouth by a horizontal partition 96, the interior of 105 said hollow device being adapted to contain air or any suitable gas lighter than air.

The principle of operation of the modification of the invention shown in Fig. 7 is the same as or similar to that shown in Fig. 6, except that in this instance, plural propellers, such as, for instance, two propellers 7 are reciprocated simultaneously, preferably in opposite directions, and in this case the slideable member 16^a is extended downwardly longer than shown in Figs. 1, 10, 13 and 15, the extreme lower portion or end being provided with a magnetic or iron portion 97 which is vertically reciprocated by means of an upper electric solenoid 98 in the 110 same manner as the modified form shown in Fig. 6, except that the electric current flows first into the upper solenoid to first move the member 16^a upwardly while the same electric current flows out of the said upper solenoid and into the lower solenoid 26, moving the member 76 downwardly, simultaneously, the electric current and speed of the reciprocating motion of the members 16^a and 76, and thereby the upper and lower propellers 115 120 125 130

- 7 being regulated and controlled by means of an electric rheostat 94. However, I wish it understood that, if desired, I may substitute the electric switch 90 in Fig. 6 instead 5 of said rheostat 94, or vice-versa, the lower end of the propeller 7 in this instance, being provided with a vertical rim 99^a extending downwardly from the horizontal partition 96.
- 10 Referring to the modification shown in Fig. 9, the center longitudinal section of the propeller 7 is formed substantially similar to a section of a common airplane wing and is, in this case, fastened to the extreme upper end or portion of the driving rod 21, which rod moves or reciprocates the propeller 7 in a vertical and longitudinal oscillating motion or orbit, or back and forth rocking motion, as will noted by the different 15 positions indicated by the dotted lines in Fig. 9, its vertical motion fore and aft being indicated by the arrows 101 and 102, respectively, it being seen in the present instance, that the driving rod 21 and crank 24 are disposed at right angles to the relative 20 fore and aft position of the propeller 7, whereby the motion of the crank 24 as indicated by the arrows 103 tend to slightly draw the front end of the propeller 7 downwardly 25 and backwardly to propel it forward and in the next instant to change the angle of incidence of the rear portion downwardly to expose more of the underside or supporting area or surface to the flow of air currents to 30 derive a lifting effect therefrom and thus be sustained in the air while also being propelled forward at the next instant or movement repeatedly, as long as it is kept in motion by the longitudinal rotation of the crank 35 24 to reciprocate and oscillate the propeller 7, but in this case the slidble member 16^a is entirely eliminated.
- The fore and aft edges of the propeller 7 are braced and kept in proper position laterally and supported fore and aft by diagonal brace rods 104, the brace bars 10 and the double guide wheels, pulleys or pulley 40 wheels 105 being secured together by means of a plate 106 disposed on each side of said 45 guide wheels and each pair of brace bars 10, the crank 24 passing or disposed thru the extreme lower ends of the rods 104, as shown, the driving rod 21 reciprocating vertically thru and held in proper position by, 50 the guide wheels 105.
- Referring to the modified form of the invention shown in Fig. 10, 107 is a low hanging frame, preferably made up, in the present instance, of upper and lower longitudinal 55 angle members 108 and upper and lower fore and aft transverse angle or tube members 109, held together by means of vertical corner angle members 110 and oblique or lattice pieces 111, forming in effect, an open 60 compartment, extending preferably longitudinally and adapted to carry a suitable weight 112, which, in the present instance, is a truck or carriage which is provided with wheels or rollers 113 adapted to travel back and forth on the horizontally and inwardly disposed angle or flange of each lower lateral 65 angle member 108 which function as guideways on which the truck is movable preferably in a fore and aft direction so that the 70 said weight of said truck or carriage and its contents or load may be arranged at the will of the operator to compensate for variations between centers of weight or gravity and upward pull of the reciprocating propeller or propellers 7 under different conditions 75 of service to maintain such centers in coincidence and speeds upward and forward, or both, and to longitudinally trim the craft.
- The lifting and propelling devices in the modified form shown in Fig. 10 reciprocate 80 vertically, either both in the same direction at the same time, or preferably in opposite directions at the same time, thus in the latter case, one of said propellers 7 moving downward and sustaining the machine in the 85 air while the other propeller is on its way upward to get into position for its next downward movement.
- In order to enable the weight 112 to be adjusted in a fore and aft direction, as previously mentioned, an operating lever or arm 114 is supported by a support 115, said lever being arranged in proximity to the operator's seat 45, a vertical brace 116 being 90 provided for the support 115, a cable or belt 117 passing around or over a drum 118 and downwardly and around a left-hand guide pulley 119 and over a rear guide pulley 120 and forwardly to an eye 121 at the rear end of said weight, the other end portion of said cable passing downwardly from said drum and around a right-hand guide pulley 122 and over upper and lower front guide pulleys 123 and 124, and the free end connecting 95 with an eye 125 at the front end of said weight, so that by turning the hand-wheel 126 to the right or left the weight or truck and its load weight may be shifted forwardly or rearwardly, thus changing the tilt of the upright member 6 and the propeller or propellers 7, as the case may be, to determine 100 the forward speed of the craft, it being understood that if desired, a suitable sprocket chain passing over suitable sprocket wheels 105 may be substituted for said cable 117, drum 118, and pulleys, 119, 120, 122, 123 and 124.
- The frame 107 may, if desired, be four cornered, in which case the lower ends of each of the brace bars 10 connect with each of said 110 corners, respectively, or, if desired, the frame 123 107 may be narrower in design and the lower ends of each of said bars 10 being connected to the lateral ends of front and rear braces extending laterally from said frame to the 115 lower end of each of said bars 10, similar to 120 130

the braces 8 and 9, shown in Figs. 1 and 8. In either case, said frame is provided with front wheels 107^a and rear swivel wheels 107^b, but may, if desired, be provided with the 5 shock-absorber or cushion members 31 instead of said wheels.

In the present instance, the horizontal steering is controlled by the hand-wheel 126 and operating lever 114 and has attached to the 10 latter, above and below its pivotal point, cables 42 and 43 which are guided by pulleys 127, the steering being affected by the forwardly and rearwardly shifting of said hand-wheel.

15 In the present instance, the pole or stem member 39, instead of being vertical, as shown in Fig. 1, is tilted slightly rearwardly and the rod or bar 40 is tilted downwardly at its front end and joins a vertical crank support 20 128 and an outwardly and rearwardly extending brace member 129, the upper ends of said stem member 39 and rod 40 being secured to laterally, downwardly and rearwardly extending brace members 130, the lower ends 25 of which connect with the top of the frame 107, or lower end of the brace rods 10 and rear braces 9, as the case may be.

In the present instance, more than two or 30 only one propeller 7 may, if desired, be employed, but in this modification I have shown superposed two propellers 7, a second vertical 35 slidable member 131 being disposed next to and adapted to vertically slide or reciprocate over the upright member 6, and the member 16^a disposed upon said member 131, which latter member is actuated or reciprocated by a second driving rod 132, the upper 40 end or bearing 133 connecting with a horizontal projection 134 preferably secured by lock nuts 135, the lower end or bearing 136 connecting with a second crank or eccentric 137, the free end of which connects with or mounted 45 in a bearing in the vertical crank support 128, the forward end 138 of the crank shaft being, if desired, extended to the forward 50 end of the machine to form an auxiliary shaft adapted to be connected with any conventional form of an auxiliary or airplane propeller, not shown.

55 In the operation of the machine in the present instance, the propellers 7 are superposed or disposed one above the other in such a manner as to be reciprocated in opposite directions simultaneously, and while any form of concavo-convex propellers 7 may be employed, I have shown, in the present instance, an upper propeller 7 provided with an upper and a lower concavo-convex formed members 139 and 140, respectively, separated any suitable distance apart by means of a vertical wall or cylinder 141, and a plurality of downwardly extending ring members 142, forming outer inverted channel members or rings, said members or rings being suitably spaced apart, 60 the whole device being braced by diagonal

cross members 143 within said device and one of said cross members extending outwardly and downwardly to brace said ring members 142, the said cross members also being secured to the said vertical wall or cylinder and second vertical slidable member 131, and the underside of the lower member 140 being braced by a frame or diagonal members 144 which extend from the said slidable member 131. 70

If desired, the wall 141 may be disposed at 75 any suitable angle instead of vertical, as shown, and the upper member 139 and upper downwardly extending ring member 142 may each be of a larger diameter than the lower member 140 and lower downwardly extending ring member 142, the central hollow portion being larger at the top than at the bottom thereof. 80

In the present instance, the lower propeller 7 may also be provided with an upper 85 and a lower concavo-convex member 145 and 146, respectively, the same being braced by means of common brace members 147 disposed between said members 145 and 146, to strengthen the same and to present outer surfaces of different angles, it being understood, that if desired, the interior of said propellers 7 may contain air or any suitable gas lighter than air, it being also understood that the angle of any one of the upper and lower members 139 and 140, may also be changed, if desired, so as to present outer surfaces of different angles. 90

If desired to operate or reciprocate the plural propellers 7 independently of one another or to employ plural or independent motors or engines 148 and 149, which may, if desired, be of a different conventional type than the motor 25, such as, for instance, upright 100 motors, the free end portion or shaft 30 of the crank 24, extends clear thru and outwardly from the member 6 and enters a bearing 150 in the free end 151 of the crank 137, each of the motors being supported by the vertical supports 128 and 152, respectively. 105

110 Referring to the modified form of the invention shown in Figs. 13 and 14, it will be noted that the base or lower end of the member 6 and motor 25 are disposed at the rear end of the machine, while the operator's seat 45 is disposed at the transverse center of the machine, lateral brace bars 154 extending downwardly from the bolt or pin 10^a and connects to the lateral end of a horizontal transverse member 155, each end of said transverse member supporting a side wheel 140^a as shown, a front brace bar 157 likewise extending downwardly but forwardly to the front end of the frame 1 and to a front swivel wheel 142^a, the upper end of said bar 157 being provided with a fork member 159, each prong of said fork being secured to opposite lateral ends of the bolt 10^a, the rear end of said frame also being provided with a swivel wheel 144^a, only one of said wheels 142^a and 144^a being 115 120 125 130

adapted to touch the ground at the same time, it being understood that, if desired, the shock absorbers 31 may be substituted for said wheels.

5 As will be noted, the propeller 7 in the present instance, is made up of plural concavo-convex forms 161, each succeeding lower form being smaller than the one immediately above it, as shown, said forms 10 161 being secured together and braced by suitable diagonal brace members 162.

As a means of protecting the propeller 7 against damage if it should by accident come in contact with some other machine or foreign 15 object while in motion or otherwise, a guard 163 is disposed immediately above said device, said guard comprising fore and aft downwardly extending members 164 and 165, respectively, the lower end of the former 20 member connecting with the lower end of the front brace bar 157 and the lower end of the member 165 connecting with the upper end of a rear diagonal guard brace 166, the lower end of which is secured to a collar 167 25 secured to the member 6, as shown.

The said members 164 and 165 are connected and support a plurality of circular or ring members 168 of different sizes or diameters, as illustrated.

30 If desired, the vertical rudder 38 may be entirely eliminated and a similar rudder 169 may be disposed forward of the machine's vertical axis or center of gravity, in which case, said rudder 169 is fastened to a diagonal steering rod 170, held to the front brace bar 157 by means of upper and lower collar bands or holders 171, the lower end of said steering rod being secured to a front transverse steering rod 172.

40 However, if desired to make the machine steer more easily or quickly to the right or left, both the fore and aft ends of the machine 45 may be provided with a vertical rudder 38 and 169 to act in conjunction with each other, as illustrated in Figs. 5, 13 and 15, or if it is desired to eliminate the rear vertical rudder 38 entirely, which moves on either a vertical axis, as shown in Fig. 1, or a slightly

50 diagonal or substantially horizontal axis, as shown by Fig. 13, a second vertical rudder 173 may also be substituted therefor, which is secured to a slightly diagonal or a substantially horizontal and longitudinally ex-

55 tending pole or stem member 174, which swings or moves on a substantially longitudinal axis, the forward end of said member 174 being movably secured to the upright member 6 by means of a transverse 60 bracket member 175 secured to or passing around said member 6 and held by frictional contact by means of a bolt 176 passing thru a collar or bushing 177, a transverse rod or bar 178 being secured to the member 174, to 65 the lateral ends of which are attached right

and left-hand cables or wires 179 and 180, which pass downwardly over suitable guide pulleys or elements 181 and 182 and 183 and 184, respectively, the right-hand cable 179 passing across to and connected to the left end of the foot lever 44, and the left-hand cable 180 crossing the cable 179 and passing across to and connecting with the opposite or right-hand end of said foot lever, as illustrated in Figs. 5 and 13.

70 A cable or wire 185 extends from the right end of the foot lever 44 to the left end of the steering rod 172 and a similar cable or wire 186 extending from the left end of said foot lever and crossing the cable 185 and connecting with the right end of the steering rod 172, all as shown in Figs. 5 and 13, so that, in practice, when the operator wishes to steer to the right he pushes or moves the right end of the foot lever forward, which pulls on the cable 186, causing the rudder 169 to swing to the left and exposing the left side thereof to the passing air, forcing it and the front end of the machine to the right, or if both the fore and aft vertically disposed 80 rudders are desired to be employed, which are suitably mounted at the fore and aft ends of the machine, respectively, and at the same time the cables 42 and 180 are pulled, which in turn swing or move the rear rudder 38 to the right, exposing its right side to the passing horizontal and longitudinal air, or air currents, and the rudder 173 being swung or moved to the right on its longitudinal axis, as shown in Figs. 5 and 13, utilizing and causing 85 the wind currents thrown downwardly by the action and speed of the downward strokes of the propeller 7 while the machine is in operation, to impinge on the side of the rudder 173, thus forcing both of said rudders 90 95 100 105 110 115 120 125 130 to the right, exposing its right side to the passing horizontal and longitudinal air, or air currents, and the rudder 173 being swung or moved to the right on its longitudinal axis, as shown in Figs. 5 and 13, utilizing and causing the wind currents thrown downwardly by the action and speed of the downward strokes of the propeller 7 while the machine is in operation, to impinge on the side of the rudder 173, thus forcing both of said rudders 38 and 169 and thereby the rear end of the machine to the left and causing the machine to turn to the right on its vertical axis or center of gravity, or if desired, all three of the rudders 38, 169 and 173 may be used in conjunction simultaneously to more easily and quickly steer the machine to the right or left, as explained above.

While I have shown the preferred forms of the frame or body of the present invention, the same may be of any suitable form, such as, for instance, circular, as shown by the dotted line 187, or four cornered, as shown by the dotted line 188.

The advantage of the form of body shown by the dotted lines 187 and 188 in Fig. 14 being that it gives more horizontal space for the useful load and that numerous passengers can be seated transversely, side by side in one or more rows, whereby they can be disposed or placed as far back or as far forward as desired to produce the desired or required tilt of the member 6 and propeller 7 in flight.

The modified form of the invention shown

in Fig. 15 comprises plural or fore and aft propellers 7, which are suitably spaced apart and kept in their proper positions, relative to each other, by means of a substantially longitudinal connecting member 189, which may or may not be extensions of one or both of the members 6, as desired, the rear propeller 7 being disposed vertically, while the forward propeller 7 is disposed in a forwardly tilted position, so that the rear propeller 7 lifts directly vertically as a whole and the forward propeller 7 both lifting and propelling the machine forwardly as a whole, it being noted in Fig. 15 of the drawings that the propellers 7 have moved up into a portion of the partial vacuum space, and ready to again move downward to again create the partial vacuum space.

It will also be noted that the motor 25 in this instance, is disposed between said plural members 6, and the crank shaft 190 being provided with a universal joint 191 connecting with the crank 24 of the forward propeller 7, both the fore and aft driving rods 21 being oppositely disposed.

In the present instance, I show on the vertical member 6 the propeller 7 formed by its wall section 192 being shaped similar to the section of an airplane wing and being disposed vertically instead of horizontally, the air reaction or aerodynamical effect thru the air being similar to that in the horizontal movement thru the air of the common airplane wing, namely, the formation or creation of a vacuum space, such as a partial vacuum, approximately between the dotted line 193 and the upper or convex side of said device, similar to the vacuum produced by the previously described propellers 7, and upward air pressure, indicated by the dotted line arrow 194, below its under or concaved side to give lift or to raise or support the machine in the air. However, this form may also be provided with a vertical inner wall 195 forming a hollow portion 196, as shown in Figs. 10 and 17, the said inner wall assisting to eliminate air resistance on the lower inner wall 197 when the propeller moves rapidly upward in its reciprocating motion, while the forward or front propellers 7 are provided with substantially vertical walls or cylinders 198 of different heights and diameters forming, in effect, a plurality of inverted circular troughs.

In order to economize in space and to concentrate the weight of the motor and operator more at one point, it will be noted that in the present instance, the operator's seat 45, as well as the steering wires, rods and foot lever being carried higher, by being disposed above the motor 25.

Referring to the modified form of the invention shown in Fig. 16, in order to reduce vibration to a minimum, while in operation, the frame or body 1 is disposed below a plu-

rality or series of horizontally arranged plural propellers 7, all of which may be reciprocated by one or more motors, as desired, connected in any conventional manner to operate according to the principle of the present invention, either in series or independently, as desired, the direction of flight being in the direction indicated by any one of the arrows 199, 200 or 201, as desired, the general construction and mode or principle of operation of each individual propeller 7, in unison with one another is preferably the same or similar to the forms shown and described in this specification.

The modified reciprocating propeller shown in Fig. 2 is constructed of a plurality of concavo-convex forms 202, preferably of a substantially 45 degree wall and of like diameters, superposed one above the other and provided with intermediate open spaces 203 between the same and being braced by suitable diagonal brace rods 203 and horizontal brace rods 204.

The modified form of the propeller 7 shown in Fig. 3 is constructed substantially of a semi-circular form 205 and is also braced by similar diagonal brace rods 206 and horizontal face rods 207, or said device may, if desired, be extended downwardly beyond its center line, in which case it may also, if desired, be provided with a vertical inner side wall similar to the wall in Fig. 17 as indicated by the dotted line 208 in Fig. 3.

The modified form of propeller 7 shown in Fig. 4 is made up of one concavo-convex form 209 and a plurality of circular walls 210 extending diagonally and downwardly from the underside of said device, said circular walls being of different diameters and braced by diagonal brace rods 211 and horizontal brace rods 212.

I wish to have it understood, that if desired, I am free to employ any shape, form or type of concavo-convex reciprocating propeller, singly, plurally, or interchangeably, or different plural forms at the same time, within the scope of the allowed claims of the present application.

The arrow 213 in Figs. 1, 5, 6, 7, 9, 10, 13, 14 and 15 indicates the direction of flight, while the numeral 214 in Figs. 1, 9, 13 and 15 indicate the approximate vertical axis or center of gravity or weight of the machine. However, I also wish to be free to change the tilt or angle of the propeller or propellers 7 downwardly at the forward end to any suitable degree in the modified forms of the invention shown in Figs. 6, 7, 9, 10 and the forward propeller 7 and member 6 of Fig. 15, thus changing the vertical axis and center of gravity or weight of the forms of the invention shown in said Figs. 6, 7, 9, 10 and 15 to correspond more with the vertical position of the member 6 in said figures, such as, for instance, as in

dicated by the dotted line 214 in Fig. 6, in which case the movable upright member 76 comprises the vertical axis of said machine instead of the broken line 99 in Figs. 6, 7
5 and 10.

From the foregoing description, taken in connection with the accompanying drawings, it will also be noted that the degree of the normal forward tilt of the machine
10 is shown to be permanently fixed in Figs. 1, 8, 13, 14 and 15, while Fig. 10 shows the degree of the machine's forward tilt to be adapted to be changed or adjusted at will.

It will be further noted that the common
15 airplane propeller and the common horizontal rudder are eliminated as being unnecessary in the present invention.

I claim:

1. A propeller having the lower edge or
20 portion of its outer or convexed surface disposed inwardly.

2. A propeller provided with a lower inwardly disposed outer or convexed surface closed against the passage of air therethru.

25 3. A propeller having its wall closed against the passage of air therethru, and the lower edge or portion of the outer or convexed surface of said wall disposed inwardly.

4. A propeller having its wall closed
30 against the passage of air therethru, said propeller having the lower edge or portion of its outer or convexed surface disposed inwardly, and said propeller provided with a relatively small opening thru its upper portion.

5. A propeller closed against the upper passage of air therethru, and the lower edge or portion of its outer or convexed surface disposed inwardly.

40 6. A propeller having concaved and convexed surfaces of different angles of incidence, and the lower edge or portion of the outer or convexed surface disposed inwardly.

7. A non-foldable propeller having a concavo-convex wall, a substantially vertical wall within the concaved side of said wall, and said walls closed against the passage of air therethru.

45 8. A propeller having upper and lower non-foldable concavo-convex formed members closed against the passage of air therethru, a substantially vertical wall between said upper and lower members, the outer side of said wall provided with one or more inverted channel members, and said channel members disposed between said concavo-convex members.

9. In a flying machine, a propeller provided with a lower inwardly disposed outer
50 or convexed surface closed against the passage of air therethru, and said propeller placed on the center of gravity of said machine and actuated by suitable power.

10. In a flying machine, a propeller closed
55 against the passage of air therethru, said

propeller having the lower edge or portion of its outer or convexed surface disposed inwardly, and said propeller placed on the center of gravity of said machine and actuated by suitable power.

70

11. In a flying machine, a propeller closed against the passage of air therethru, said propeller having the lower edge or portion of its outer or convexed surface disposed inwardly, said propeller movably mounted on an upright member, suitable power for actuating said propeller, and a weight adapted to be moved at will.

75

12. In a flying machine, a propeller closed against the passage of air therethru, said propeller having the lower edge or portion of its outer or convexed surface disposed inwardly, said propeller movably mounted on an upright member, suitable power for actuating said propeller, and said machine provided with a plurality of cushion or shock-absorber members.

80

13. In a flying machine, a plurality of propellers closed against the passage of air therethru, said propeller having the lower edge or portion of its outer or convexed surface disposed inwardly, said propellers movably mounted on one or more upright members, suitable power for actuating said propellers simultaneously, and the center of lift of said propellers placed on the center of gravity of said machine.

90

14. In a flying machine, a propeller closed against the passage of air therethru, said propeller having the lower edge or portion of its outer or convexed surface disposed inwardly, said propeller movably mounted on an upright member, a frame disposed below said propeller, and said propeller placed on the center of gravity of said machine and actuated by suitable power.

100

15. In a flying machine, a propeller closed against the passage of air therethru, said propeller having the lower edge or portion of its outer or convexed surface disposed inwardly, said propeller movably mounted on an upright member, suitable power for actuating said propeller, a frame disposed at the lower end or portion of said member, said frame carrying a weight adapted to be moved at will by a hand-wheel revolving a drum, a cable passing over or around said drum, and each end of said cable connected to said weight.

110

16. In a flying machine, a propeller closed against the passage of air therethru, said propeller having the lower edge or portion of its outer or convexed surface disposed inwardly, said propeller movably mounted on an upright member, a vertical rudder, and said propeller placed on the center of gravity of said machine and actuated by suitable power.

120

17. In a flying machine, a propeller closed against the passage of air therethru, said

130

propeller having the lower edge or portion of its outer or convexed surface disposed inwardly, said propeller movably mounted on an upright member, said propeller placed on the center of gravity of said machine and actuated by suitable power, and a crankshaft extending from said power and adapted to actuate an auxiliary propeller.

18. In a flying machine, a propeller closed
10 against the passage of air therethru, said propeller having the lower edge or portion of its outer or convexed surface disposed inwardly, said propeller movably mounted on a hollow upright member, said member containing a liquid storage compartment, and said propeller placed on the center of gravity of said machine and actuated by suitable power.

19. In a flying machine, a propeller closed
20 against the passage of air therethru, said propeller having the lower edge or portion of its outer or convexed surface disposed inwardly, said propeller movably mounted on an upright member, the upper end of said member provided with a projection, and said propeller placed on the center of gravity of said machine and actuated by suitable power.

20. In a flying machine, a propeller closed
30 against the passage of air therethru, said propeller having the lower edge or portion of its outer or convexed surface disposed inwardly, said propeller slidably mounted on an upright member, and suitable power for actuating said propeller on said member.

CHARLES W. WALLER.
